UNITED STATES PATENT OFFICE.

FREDERICK W. BERNAU, OF NEWARK, NEW JERSEY.

DATE PRINTER.

Application filed October 24, 1921. Serial No. 510,028.

To all whom it may concern:

Be it known that I, FREDERICK W. BERNAU, a citizen of the United States, residing at Newark, in the county of Essex and State of New Jersey, have invented certain new and useful Improvements in Date Printers, of which the following is a specification.

This invention relates to an automatic date printer for adding, subtracting, or listing machines having printing mechanism.

While the present invention may be used in connection with any adding, subtracting, or listing machine having printing means, and a traveling carriage, it is particularly adapted for use with the "Ellis" machine, which is disclosed in certain patents granted to Malcolm Ellis, more particularly Patents Nos. 1,197,276 and 1,197,277, dated September 7, 1916; 1,203,863, dated November 7, 1916, and 1,219,445, dated March 20, 1917. The automatic non-printing mechanism set forth and claimed in my application Serial No. 502,858, filed September 24, 1921, may be used in connection with the present invention and with the usual printing mechanism, to enable the automatic date printing mechanism to be released to effect printing, or held back, to prevent printing the date, according to whether the item is one which requires the printing 30 of a date opposite thereto, or otherwise.

Control of my novel date printer may be effected by the position of the traveling carriage of the adding, subtracting, or listing machine on which it is used. By providing a suitable stop, adjustable as desired, the blocking or latching means for the date printer may be rendered operative or inoperative so that, according to carriage position, the date printer will be rendered operable 40 or inoperative to print the date in those columns of the ledger sheet where date is required, and when the carriage is in another position, where no date is desired to be printed in the selected column of the ledger sheet, the date printer will be latched.

The date printer is particularly useful in any ledger sheet work, for instance, where checks are to be printed and added and the dates of their deductions from the account 50 entered, or, deposits or credit items entered in bank work.

The date printer of this invention is mounted alongside the printing group and is subject to the printing action of the machine when the date printer is released but

it is held back, despite the action of any or all of the printing sectors of the printing group, when desired. The mechanism is arranged to be set by hand so that the same date will be printed over and over as long as 60 the printing mechanism remains in its set position.

The invention is not limited to the use of printing wheels but that form is shown in the drawings and hereinafter described. 65 One of the printing wheels is provided with type representing the months of the year as, for instance, "Jan.", "Feb.", "Mar.", etc., or, numeral type may be used on the month dating wheel as, for instance, "1" (to represent January); "2" (to represent February), etc. The daily printing wheel is provided with numeral type running from 1 to 31. Any suitable means, such as independent pawls or checking devices of any kind, are employed 70 to hold the respective printing wheels where set. During the month of January, for instance, the printing wheel will remain in a given set position. When that month has expired, the month printing wheel will be 75 turned one step to present the "Feb." type, etc. Each day, the operator will turn the day printing wheel to present to the printing line the particular day of the month as "1", "2", "3", etc.

It is to be understood that no keys are provided on the keyboard of the adding, subtracting, or listing machine equipped with my invention for the purpose of effecting printing of the date or turning the date 90 wheels. Once the wheels of the date printing mechanism are set, however, the mechanism is ready to act when the machine goes through its cycle of operations and effects printing, unless the date printer is latched as 95 hereinbefore set forth. The date printer is automatically restored to normal position in the same manner that the printing group is restored, as explained in the Ellis patents hereinbefore enumerated.

The invention is susceptible of modification and the disclosure thereof, is, consequently, to be considered as illustrative, instead of in limitation, of the scope of the invention.

In the accompanying drawings:

Figure 1 is a side elevation showing the date printer combined with a disclosure of so much of printing mechanism of the "Ellis" machine as will afford a clear understanding 110

thereof, certain parts being in dotted lines to prevent obscuring the present invention.

Fig. 2 is a front elevation of the date printer, showing the printing group of the "Ellis" machine in full lines; and

Fig. 3 is a detail plan view in full and dotted lines, showing forms of a stop which may be used on the carriage for the control of the date printer.

10 The present invention is shown in the drawings, and hereinafter described, in connection with the printing group of the "Ellis" machine. In that connection reference may be had to the Ellis patents hereinbefore enumerated.

The platen which is carried by the traveling carriage of the Ellis machine appears at S and the rack stop bar which is located at the front of the carriage appears at C91.

20 One of the stops (of which as many as desired may be employed), is shown at 1, being adapted to be positioned at any point of the rack stop bar C91 as shown generally in Figs. 2 and 56 of the Ellis Patent No.

25 1,197,276. In the Ellis machine the rack stop bar C91 may carry a number of adjustable stops, set at desired positions, controlling various functions of the machine by the position of the traveling carriage. In connection with the present invention, as with the automatic non-printing mechanism of my co-pending application Serial No. 502,858, filed September 24, 1921, one or more of the stops 1 may be used to control the operation of the printing arms P52 of the usual printing group and the operation of the date printer which is combined with said printing group, by cooperation of the beveled point 1^b with the point 5^a carried by the

40 blocking bail 5, 6, which is pivoted at 4 to the upright arms 2. The arms 2 are securely fastened by rivets or other fastenings 3 to the vertical side plates P50, P51, attached to the frame of the machine. A bracket 2^a will be used for connecting one of the arms 2 to the plate P51.

50 So much of the printing group and its related parts is shown as will afford an understanding of the relationship of the present invention thereto and its operation, reference being had to the Ellis patents hereinbefore enumerated for a further disclosure of construction and operation of the mechanisms having to do with the printing group.

55 The printing arms appear at P52. They are modified, as set forth in my co-pending application Serial No. 502,858, filed September 24, 1921, by the provision of the fingers a for engagement by the bail 5, 6.

60 The printing arms P52 are normally held in retracted position by a common printing trigger 57P which engages fingers on the rebound members P62 of which there is one for each printing arm as shown, for instance, in Patent No. 1,219,445. The opera-

tive connection between each printing arm P52 and its rebound number P62 is the rebound rocker 58P pivoted at P16 to the printing arm P52.

The piece P58, set forth in the Ellis patents, is connected by springs P85 to the rebound rockers 58P and other springs 80P are used to effect printing when printing trigger 57P is unlatched from the rebound members P62 provided the bail 5, 6, is free of the fingers a.

70 The rebound bar appears at P18. The "0" printing triggers are shown at P57.

The printing sectors P54 which are pivoted to the arms P52 at P10, bear the type 80 which strike the platen S when printing is effected; these printing sectors P54 are set from the reciprocatory racks or actuators of the machine, through suitable intermediate mechanism, by connecting rods P53, as will 85 be clear from the Ellis patents hereinbefore enumerated.

The automatic date printer.—The mechanism for printing the date is located at the left hand side of the printing group P52 and 90 arranged to print the date on the same line with the number printed by the printing sectors P54 when said date printer is operated. The date printer is located between the left hand vertical arm 2 and the printing group P52 and is carried by an arm P252 which is mounted at P34P to swing on the same center as arms P52. The arm or frame P252 is provided with a finger a' 95 corresponding to the fingers a which is adapted to be engaged by the bail 6 to hold back the latch of the date printer so that it cannot operate if a suitably set stop 1 on the rack stop bar C91 engages the point 5^a, without, however, holding back the printing arms P52 on account of the cut out or narrowed part 6 being provided.

100 I wish it understood, however, that the particular form of bail 5, 6, 6^a, which is shown, is not essential in connection with the date printer and that, as explained in my co-pending application Serial No. 502,858, filed September 24, 1921, other forms of bails, whether solid or multiple, and other forms of points and stops may be used according to the conditions which it is desired to meet.

110 The bail 5, 6, is normally held in released or raised position by spring 7 connected to stops 8 on the bail and arm 2 and consequently it is necessary for a stop on the carriage to depress the bail to cause it to latch the printing arms P52 and date printer arm P252.

115 The arm P252 is provided with a companion rebound member P62 and a rebound rocker 58P and is operated by springs P85 and 80P and is locked by the printing trigger 57P and cooperated with by the piece P58, the same as is the case with the 120

printing arms P52. Consequently, the date printer will operate to print the date at the same time the printing arms P52 print the number unless the block or locking bail 5, 6, has been depressed by a stop 1 on the carriage.

A month dating wheel P75, and a day dating wheel 75P, each provided with raised type, are loosely mounted on screws P28P carried by the arm or frame P252 and they have the ratchet wheels P75^a and 75P^a. Pivoted to the frame or arm P252 are pawls P60P and P60P^a which are provided with rollers 37P and which, respectively, engage the ratchet wheels P75^a and 75P^a. The pawls are held against the ratchet wheels by similar coil springs 81P and P81.

The month wheel P75 may be provided with type representing abbreviations of the month such as "Jan." "Feb." "Mar." etc., or numeral type may be used thereon such as "1," "2," "3," etc., to designate the groups of month type arranged around the periphery of the wheel. The day wheel 75P is provided with one or more sequences of number type running from 1 to 31, to represent the days of the month.

The wheel P75 remains after being set, as long as the given month continues and is then turned to present type representing the succeeding month to the printing line. Each day the operator turns the wheel 75P to bring the day of the month to the printing line.

It will be observed that the operation of the date printer is automatic, each time the printing group P52, P54, operates but in ledger sheet work there are only certain columns where it is desired to print the date ahead of a debit or credit item. An instance is ledger work for banks where deposits and checks require the printing of the date in advance of the items in the respective columns and so does the printing of the new balance but in the columns where items are printed in picking up the old balance and where the balance is brought forward, the date need not be printed. To take care of such requirements and any others which may become necessary, the provision of one or more stops 1 on the stop rack bar C91 brings about a non-print condition so far as the date printer is concerned when the carriage is in predetermined position corresponding to the columns of the ledger sheet. At such times the stop 1 depresses the bail 5, 6, and locks the arm or frame P252 so that the date will not be printed although desired ones of the printing group P52, P54, will print. The control of the printing arms P52 is not necessarily related to the control of the date printing arm P252 as it is well within the spirit of my invention to provide for locking or releasing the date printing arm P252 by its own bail 5, 6,

and stop on the rack stop bar C91 without regard to how the printing group P52, P54, is locked or "split."

I claim:

1. In an adding, subtracting, or listing machine, the combination with a numeral printing group adapted to print the results of settings of the machine when the latter is operated, of a normally operative self-contained manually-settable date printer on which the date may be set up at will independently of the operation of the machine, said date printer, unless restrained, being adapted to automatically operate to print a date associated with the number printed by said printing group when the machine is operated, said date printer being operated by the same mechanism that operates the printing group so that it is normally adapted to print the date when an item is printed by the printing group, and means for preventing, at will, the operation of the date printer, to thereby eliminate date printing.

2. In an adding, subtracting, or listing machine, the combination with a numeral printing group adapted to print the results of settings of the machine when the latter is operated, of a normally operative self-contained manually-settable date printer on which the date may be set up at will independently of the operation of the machine, said date printer, unless restrained, being adapted to automatically operate to print at date associated with the number printed by said printing group when the machine is operated, and means for preventing, at will, the operation of the date printer to thereby eliminate date printing.

3. In an adding, subtracting, or listing machine, the combination with a traveling carriage, and a platen carried thereby, of a printing group comprising type carriers movable toward and away from the platen, an automatically acting date printer movable toward and away from the platen for printing a date associated with the number printed by the printing group, and means controlled by the carriage for rendering the date printer effective or ineffective according to the position of the carriage.

4. In an adding, subtracting, or listing machine, the combination with a traveling carriage, and a platen carried thereby, of a printing group comprising type carriers movable toward and away from the platen, an automatically acting date printer movable toward and away from the platen for printing a date associated with the number printed by the printing group, and means for automatically locking and restraining the date printer to prevent it from operating when the carriage is in predetermined position or positions.

5. In an adding, subtracting, or listing

- machine, the combination with a traveling carriage, and a platen carried thereby, of a printing group comprising type carriers movable toward and away from the platen, 5 an automatically acting date printer movable toward and away from the platen for printing a date associated with the number printed by the printing group, and means for automatically locking the date printed 10 to prevent it from operating when the carriage is in a predetermined position or positions, comprising a latch adapted to engage and restrain the date printer, and an adjustable stop on the carriage adapted to 15 cause the latch to lock the date printer.
6. In an adding, subtracting, or listing machine, the combination with a platen, of
- a group of numeral printing types adapted to be moved toward the platen to effect printing according to the setting of the machine, a self-contained date printer comprising a member adapted to be moved toward the platen, manually settable date printing types mounted on, and movable with, said member and adapted to be brought to the 20 printing line of the printing types aforesaid to print a date associated therewith, and means for restraining, at will, the movement of the date-printer-carrying member to thereby prevent printing of the 25 date.

In testimony whereof I affix my signature.

FREDERICK W. BERNAU

Certificate of Correction.

It is hereby certified that Letters Patent No. 1,518,478, granted December 9, 1924, upon the application of Frederick W. Bernau, of Newark, New Jersey, for an improvement in "Date Printers," were erroneously issued to the inventor, said Bernau, as owner of said invention, whereas said Letters Patent should have been issued to *Ellis Adding Typewriter Company, of Newark, New Jersey, a Corporation of New Jersey*, as assignee of the entire interest in said invention, as shown by the records of assignments in this office; and that the said Letters Patent should be read with this correction therein that the same may conform to the record of the case in the Patent Office.

Signed and sealed this 6th day of January, A. D. 1925.

[SEAL.]

KARL FENNING,
Acting Commissioner of Patents.
